SNOWBALL SHAVER

John Ragolio, Baltimore, Md.

Application May 21, 1948; Serial No. 28,371

2 Claims. (Cl. 241—92)

1

This invention relates to machinery for the fracturing of materials and more particularly to those employable for the shaving of ice.

Among the objects of this invention is to provide a new and improved ice chipping machine that will do such work, effectively and efficiently, at the same time being compact and easily manipulated.

A further object of this invention is to provide a new and improved ice-shaving machine that will automatically shave off pieces of ice from a block or section of ice by shaving and avoiding undue breaking and then direct them through a suitable channel to a compartment selected therefor and adapted to facilitate their removal. This all being done without the use of weights or springs to force the ice down in the machine.

Other objects of the invention will be indicated as it is further described.

For a better understanding of the invention and the objects and principles thereof, reference is made to the appended drawings, and the description following, which together describe a particular form of the invention by way of example, while the scope of the invention is emphasized in the claims.

In the drawings:

Figure 1 is a plan view of an ice shaving machine embodying this invention, with portions broken away to show the interior construction;

Figure 2 is a front elevation of Figure 1 with portions broken away to show the inner construction;

Figure 3 is an end elevation of the machine with portions broken away to show its inner construction;

Figure 4 is partial sectional elevation taken on line 4—4 of Figure 1;

Figure 5 is a view looking from above taken on line 5—5 of Figure 4;

Figure 6 is a view taken along line 6—6 of Figure 3;

Figure 7 is a sectional view through 7—7 on Figure 6;

Figure 8 is a detail of the shaver plate used in this embodiment; and

Figure 9 is a detail of the knife used in the shaving plate and taken on line 9—9 of Figure 8.

Similar reference characters relate to the same parts throughout the various views.

In the construction particularly indicated in the drawings, a housing 10 of thin flat material is formed to a rectangular contour having an upper shell 9 surmounted on a hollow base 11 raised

substantially above level to contain a pan 12 and provide for ample space 13 in which to manipulate it. An opening 14 enables the pan 12 to be handled appropriately.

5. The upper shell 9 of the housing 10 is divided substantially into halves by a tank 15 vertically erected in it. An opening 16 is provided in the tank 15 and serves as a large orifice. A hopper 17 having one side vertical and substantially open 10 at 18 with the opposite side 19 converging towards the bottom, serves as a container for relatively large pieces of ice. The converging side 19 serves to press the ice towards the open side and the opening 18. The hopper 17 has an extending lip 20 at its bottom to facilitate the retention of the hopper on the edge of the tank 15, as well as prevent leaks of ice or water occurring inside the space 21 in which the hopper 17 is situated. The hopper has a continuous 15 flange 22 around it about the vertical side, having holes 23 spaced along it for bolts to secure it to the tank 15. The hopper 17 has a cover 24, together with lock 25 and hinges 26.

The chipping and shaving mechanism of the 25 machine consists of a chipper or shaver plate 27 of disc-like form with slots 28 formed with bevels 29, against which the knives 30 rest and project beyond slightly, for chipping purposes. Back of the slots 28 are raised ridges 49 serving to gather 30 the ice chipped by the knives on the plate, and carry it forward from the hopper. This chipped or shaved ice is thrown from the plate against the wall guards 31 of the tank 15 surrounding the plate 27 and diverted to a floor opening 32 in the base 11 and dropped into the pan 12. The plate 27 is mounted on a shaft 33 journaled in the tank 15 and operated through a pulley 45 and belt 34, actuated by a motor 35. The motor 35 is attached to the base 11 and energized by 40 an outside source of power, not shown, which is controlled by a switch 47. The knives while rotating run close to the surface of the partition but do not scrape against it, although they do engage the face of the ice as it comes through the 45 opening, and chip or scrape it off. The ice to be scraped is placed in the hopper and allowed to slide forward and down as it is scraped or chipped off.

While but one general form of the invention 50 is shown in the drawings and described in the specifications, it is not desired to limit this application for patent to this particular form or in any other way otherwise than limited by the scope of the claims, as it is appreciated that other forms of construction could be made that

would use the same principles and come within the scope of the appended claims.

Having thus described the invention, what is claimed is:

1. A machine of the kind described, comprising a housing having an upper left hand compartment, an upper right hand compartment and a lower compartment, a hopper completely enclosed within the upper left hand compartment, said hopper having an opening flush with the top of said housing and a wall tapering inwardly towards the bottom of the upper right-hand compartment and having a terminal turned-down lip extending in said last-named compartment, a tank in the upper right hand compartment, said tank having a straight wall therein terminating in a flaring wall portion extending towards the lower compartment, said hopper and tank having open sides in juxtaposition, a shaver plate carried by said tank and journaled in the straight wall portion thereof, means for rotating said shaver plate and a pan in the lower compartment to receive the ice fed to said hopper, shaved by said shaver plate and guided by the flaring wall portion on said tank and by said lip. 10 15 20 25

2. A machine as set forth in claim 2, said hopper and tank having interlocking portions and flange connections and said means for driving the shaver plate comprising a motor in the upper right hand compartment, and connecting means between said motor and plate.

JOHN RAGOLIO.
